FIG. 1 is a front elevational view of a computer display with double helix interface, showing an opaque embodiment of my new design;

FIG. 2 is a partial enlarged view taken from line 2-2 on FIG. 1;

FIG. 3 is a front elevational view of a computer display with double helix interface, showing a transparent embodiment of my new design; and,

FIG. 4 is a partial enlarged view taken from line 4-4 on FIG. 3.

The broken lines depict environmental matter and form no part of the claimed design. The dashed-dot lines showing a portion of the display screen form no part of the claimed design. The broken away symbols indicate that the appearance of any portion of the article between the break lines forms no part of the claimed design.
